BIFOLD PORTFOLIO

Randolph G. England, 3865 W. 33rd St.,
Cleveland, Ohio 44109

Filed Aug. 12, 1963, Ser. No. 76,187

Term of patent 3½ years

(Cl. D87—3)

FIGURE 1 is a front elevational view of a bifold portfolio showing my new design;

FIGURE 2 is another front elevational view with a portion of the front broken away;

FIGURE 3 is a rear elevational view;

FIGURE 4 is a plan view of the inside of the bifold portfolio when in a spread-out position;

FIGURE 5 is a side elevational view in a partially open position; and

FIGURE 6 is a side elevational view thereof in a closed or carrying position.

A feature that is characteristic of the design of my bifold portfolio resides in the combination, together with a pair of panels separated from each other by flat straps, of a pair of disproportionately sized pockets, each with an associated flap, which form part of the front or exposed face of one of the two halves of the portfolio, said disproportionately sized pockets being positioned in said panels midway between the top and bottom edges of the portfolio; i.e., in transverse symmetry with respect to the horizontal or major axis of such front or exposed face.

I claim:

The ornamental design for a bifold portfolio, as shown and described.
